CONTROLLING MECHANISM FOR PRESSURE BAND

Thomas M. Knowland, Belmont, Mass., assignor, by
mesne assignments, to American Biltite Rubber Com-
pany, Inc., a corporation of Delaware

Filed Dec. 26, 1956, Ser. No. 630,586

4 Claims. (Cl. 18—6)

This invention comprises improvements in machines for curing or vulcanizing rubber or plastic compounds in sheet form and which include in their structure a rotary cylinder, a cooperating pressure band and guide rolls arranged to lead the band in a substantially triangular path including a partial encirclement of the cylinder.

In machines of this type difficulty has been encountered under some circumstances in maintaining true running of the pressure band. Loss of time and annoyance have been caused by the tendency of the pressure band to drift or work toward one edge or other of the cylinder as it rotates hour after hour in operation. Attempts to confine the pressure band forcibly to the true path have not proved practicable because they tend to deform the band itself and to create excessive and undesirable friction. Other attempts to solve the problem have been made by providing for adjustment of one of the guide rolls angularly in a horizontal plane and while this expedient has been successfully practiced it has certain disadvantages besides not being adapted for the latest type of machines such as that disclosed in United States Letters Patent 2,656,565, Apel and Collins, wherein the tension-exerting guide roll is supported by bearing arms pivoted to swing about a horizontal axis.

I have discovered that an extremely accurate and sensitive control of the path of the pressure band may be achieved by providing means for adjusting one of the bearing arms of the roll in a direction at substantially right angles to the line of pressure between the cylinder and the guide roll or as herein shown in a vertical direction. It has been found that when a single bearing of the tension roll is vertically displaced downwardly in relation to the opposite bearing the pressure band as it approaches the roll will be led to travel laterally away from the bearing that has been dropped. Conversely, it has been found that when the same bearing is displaced vertically upwardly the pressure band will begin to travel laterally toward the raised bearing. The effect of such adjustment is to vary the angle of approach of the band to the tension roll and thus to cause the band to travel in the desired selected direction. Moreover, this takes place without straining the marginal portions of the band beyond the elastic limit, an occurrence which will eventually destroy the useful life of the band.

An object of the invention is to provide mechanism which may be easily operated at all times for effecting the desired adjustment under the tremendous pressure and weight of moving parts always subjected to a hydraulically developed tension of as much as 30 to 40 tons in the steel pressure band. This in some instances is 72" in width. Such a band is the subject-matter of United States Patent No. 2,083,257, Bierer.

A construction of band controlling mechanism which has proved satisfactory under these severe conditions includes in its organization a roll-supporting arm mounted to rock upon a pivot pin carried eccentrically by a pair of spaced disks which furnish support for both ends of

2

the pin and by their rotation adjust its position and the roll-supporting arm.

These and other features of the invention will be best understood and appreciated from the following description of preferred embodiments thereof selected for purposes of illustration and shown in the accompanying drawings in which:

Fig. 1 is a view of the entire machine in side elevation,
Fig. 2 is a view of the machine in rear elevation, and

10 Figs. 3-7 are detailed views of the mechanism for vertically adjusting one of the bearing arms of the tension roll.

The machine herein shown is in general construction similar to that of United States Letters Patent 2,656,565 15 mentioned above to which reference may be had for further details of construction.

As herein shown the machine comprises a main frame 10 in which a heated cylinder 11 is journaled for rotation about a horizontal axis. Guide rolls 12, 13 and 14 20 are mounted upon the frame in such position as to guide a steel pressure band 15 in a substantially triangular course which includes partial encirclement of the cylinder 11. The roll 12 is mounted to rotate about a stationary axis. The roll 13 is driven through suitable connections by a motor 15 and is bodily movable toward and from the cylinder 11 to regulate the entering pressure at the bite of the band and cylinder upon the uncured stock as it enters the machine. The vulcanizing or curing operation is effected as the material passes about the circumference of the cylinder 11 while subjected to pressure against the cylinder by the pressure band 15.

The tension roll 14 has a shaft 16 and this is supported normally for rotation about a horizontal axis at substantially the same level as the axis of the cylinder by bearing arms 17 and 18. The arm 17 which is on the right side of the machine as shown in Fig. 2 is supported by a short shaft 19 carried by a bracket 20 bolted in stationary position to the frame 10. The bearing arm 18 is supported by a pin 21 best shown in Fig. 6 carried eccentrically by and between a pair of flanged disks 22 and 23. These disks are mounted on roller bearings in the arms of a forked bracket 24 having connecting strengthening webs 24' and the pin 21 is supported at its opposite ends by the spaced disks. The bracket itself is suspended 30 upon a stud 25 which projects horizontally from a pad 26 bolted to the frame 10. Roller bearings are interposed between the stud 25 and the bracket, thus permitting a slight rocking of the bracket in accommodating vertical adjustment of the bearing arm 18. A lubricating thrust block 27 is secured to the pad 26 in position to engage the web 24' of the bracket near its lower edge.

The flanged disk 23 from which projects the eccentric pin 21 is itself provided with an outwardly extending shaft 28 to which is keyed a worm wheel 29. This in turn meshes with a worm 30 which is enclosed in a casing bolted to one side of the bracket 24 and provided with an outwardly extending shaft 31 terminating in a hand wheel 32. It will be seen that by turning this hand wheel the disk 23 will be rotated and the eccentric pin 21 lifted or lowered as the case may be. The flanged disk 22 will be correspondingly rotated by the eccentric pin 21 and thus both ends of the pin are evenly supported in all positions of adjustment.

65 The amplitude of adjustment required to shift the path of travel of the pressure band 15 is slight but if desired self-aligning bearings may be provided for the shaft 16 where it is supported by the pivoted arm 17.

The arms 17 and 18 are connected to hydraulic cylinders 34 and these are pivotally connected at one end to the top of the frame 10 and act to maintain continuous outward thrust upon the bearing arms and so to subject

the pressure band 15 to substantial extension. The arms 17 and 18 are provided with outward extensions in which is journaled a guide roll 35 acting to deflect the cured or vulcanized sheet from the pressure band 15 at the conclusion of the curing or vulcanizing operation.

It will be apparent from the foregoing description that the adjustment provided for the roll 14 is in a direction at substantially right angles to the line between the axes of the cylinder 11 and the roll 14, this being the line of resultant pressure caused by the band tension. Adjustment of this type is effective to change the angle of approach of the pressure band to this roll 14 by twisting the band without appreciably stretching either marginal edge therefor.

Having thus disclosed my invention and described in detail an illustrative embodiment thereof, I claim as new and desire to secure by Letters Patent:

1. Band controlling mechanism for a vulcanizing machine or the like having a heated cylinder rotatable about a horizontal axis, an endless pressure band and guide rolls arranged to lead the band in a path including a partial encirclement of the cylinder; said mechanism comprising pivotally mounted roll-carrying arms, fluid pressure means for swinging said arms in a direction away from the cylinder thereby maintaining the band under substantial linear tension, and means for raising and lowering one of said arms thereby causing the guide roll to twist the band transversely without elongating either edge thereof.

2. Band controlling mechanism as defined in claim 1, further characterized in that the means for raising and lowering the said roll-carrying arm comprises a forked bracket carrying spaced flanged disks, a pivot pin for the arm eccentrically secured to said disks, and worm and

wheel mechanism for rotating the disks for adjusting the position of the said pivot pin.

3. Band controlling mechanism as defined in claim 1, further characterized in that the means for raising and lowering the roll-carrying arm comprises a bracket pivotally mounted for movement about an axis at right angles to the axis of the arm and having a lubricating thrust block supporting it at a distance from its pivotal axis.

10 4. Band controlling mechanism as defined in claim 1, further characterized in that the means for raising and lowering the roll-carrying arm comprises a forked bracket having a pair of disks mounted on roller bearings in spaced relation therein and connected by an eccentric 15 pivot pin, a worm wheel connected to one of said disks, and a manually operable worm meshing with the said worm wheel.
